CLAIM

The ornamental design for a handgun display and storage rack, as shown and described.

DESCRIPTION

FIG. 1 is a top, front, and right side perspective view of a handgun display and storage rack;

FIG. 2 is a bottom rear and left-side perspective thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left-side elevational view thereof, the right-side elevational view being a mirror image thereof; and,

FIG. 8 is a top, front, and left-side perspective view thereof. The broken line showing in the figures is included for the purpose of illustrating portions of the handgun display and storage rack for handguns and form no part of the claimed design.
